DISPLAY STAND FOR DOLLS AND DOLLS' CLOTHING

David Kass, Roosevelt, N.Y., assignor to Original Toy Corporation, Brooklyn, N.Y., a corporation of New York

Filed June 3, 1964, Ser. No. 80,251

Term of patent 14 years

(Cl. D80—9)

FIG.2

FIG.5

FIG. 1 is a perspective view of a display stand for dolls and dolls' clothing, showing my new design;

FIG. 2 is a top plan view of the same;

FIG. 3 is a bottom plan view of the center shelf thereof;

FIG. 4 is a bottom view of the display stand; and

FIG. 5 is an elevational view of the center shelf thereof, the rest of the stand being broken away for convenience of illustration.

The stand is shaded to indicate contrast of color.

I claim:

The ornamental design for a display stand for dolls and dolls' clothing, substantially as shown and described.
